MICHIGAN.

WATER-DISTRIBUTING MEANS.

1,357,840.

Specification of Letters Patent.

Patented Nov. 2, 1920.

Application filed April 21, 1917. Serial No. 163,682.

To all whom it may concern:

Be it known that I, JOHN A. BROOKS, a citizen of the United States, and a resident of Toledo, in the county of Lucas and State 5 of Ohio, have invented a certain new and useful Water-Distributing Means; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 This invention relates to water distributing means, and particularly to means for controlling the successive distribution of water to different discharge pipes in a multiple pipe sprinkling or water supply system.

20 In most public water supply systems residences are provided with water mains which are too small to supply more than three or four sprinkler heads at one time without a material loss of pressure, and it has therefore been necessary in equipping lawns with 25 sprinkling systems to either provide a plurality of supply mains, each having a limited number of sprinkler heads, or to permit one set of sprinklers to operate for a 30 while, and then another, and so on until the area to be watered has been covered.

The primary object of my invention is the provision of simple and efficient means which is automatically operable to obtain a 35 timed successive distribution of water to different distributing lines from a common source of supply, whereby to obviate the necessity of having different distributing means and also of manually attending to the 40 turning on and shutting off of water in different distributing lines in order to keep up the distributing pressure.

The invention is fully described in the following specification, and while, in its 45 broader aspect, it is capable of embodiment in numerous forms, only a few of such forms are illustrated in the accompanying drawings, in which—

Figure 1 is a central longitudinal section 50 of the preferred form of water distributing means embodying the invention, and Fig. 2 is an enlarged fragmentary section of a portion thereof slightly modified.

Referring to the drawings, 1 designates a 55 casing of tubular form in cross-section, in

the present instance, and forming the chambers 2 and 3 in axially spaced relation, the chamber 3 being the uppermost, in the present instance, and the larger in diameter.

A water supply pipe 4 is tapped into the 60 casing 1 in communication with the upper end portion of the chamber 2, and a plurality of water distributing pipes 5, 6 and 7 lead from said chamber in substantially equidistantly spaced relation longitudinally 65 thereof and at one side of the supply pipe, as shown. The top of the chamber 3 is closed by a cap 8 having a fluid escape passage 9 therein which is normally closed to the chamber 3 by an outwardly seating valve 70 10, the stem 11 of which projects without the cap to permit the application of pressure to its outer end to unseat the valve when desired. The valve is normally held seated by a spring 12, which bears outward against 75 the collar 13 carried by the valve stem.

A plunger 14 is mounted for reciprocatory movements in the chamber 3 and has a hollow stem 15 projecting therefrom into the 80 chamber 2, said stem, in the present instance, being of sufficient length to extend to adjacent to the bottom of the chamber 2 when the plunger 14 is at the bottom of its chamber. The stem 15 carries three cups or plunger members 16, 17 and 18 which have 85 a sliding fit in the chamber 2 and are longitudinally spaced, as shown.

The stem 15 is provided with enlarged 90 openings or perforations 19 above the upper cup 16 and with outlet openings or perforations 20 between the cups 17 and 18, all of said perforations opening communication 95 between the chamber 2 and the interior of the stem. The cup 16 is so positioned that it is disposed between the water inlet 4 and the set of outlet pipes 5, 6 and 7 at all times, and the cups 17 and 18 are so positioned that they are disposed below the set of outlet pipes or at the opposite side thereof to the inlet pipe when the plunger is at the lower 100 end of its stroke, as shown in Fig. 1. The space between the cups 17 and 18 is preferably less or not greater than the space between the outlet passages of successive pipes 5, 6 and 7, so that the outlet openings 20 in 105 the stem have communication with only one outlet pipe at a time during a raising or lowering of the stem.

The plunger 14 has a small passage 21 110 therein for opening communication between

the chambers 2 and 3 through the plunger, and the passage of water through the passage 21 is regulated by a valve 22, which can be reached for adjustment purposes through 5 the top of the chamber 3 upon a removal of the cap 8. A pin 23 projects upward from the plunger 14 and acts as a stop for coacting with the cap 8 to limit the upward movement of the plunger. The chamber 2 is provided in the bottom thereof with a drainage 10 passage 24.

In the use of this form of my water distributing means it is set for operation by merely pressing on the valve stem 11 to unseat the valve 10 to release the compression 15 in the chamber 3 above the plunger 14. The water pressure which is constantly present in the chamber 2 between the plunger 14 and cup 16 due to the connecting of such space 20 with a source of water supply under pressure through the pipe 4, acts against the under side of the plunger 14 and forces such plunger and attached stem to the limit of its inward movement, it being understood 25 that the valve 10 is retained open until the plunger has reached the limit of its upward movement. The slow leakage of water through the passage 21 into the space above the plunger 14 causes the plunger and attached parts to slowly lower, the speed of 30 such lowering being determined by an adjustment of the valve 22. It will be understood that the space between the cups 17 and 18 is in communication with the source of 35 water supply through the inlet and outlet perforations 19 and 20 and stem 15 so that during a descent of the plunger and stem the water under supply pressure is first distributed to the pipe 5 then to the pipe 6 and 40 then to the pipe 7, and so on for the number of distributing pipes provided during the period of communication of the space between the cups 17 and 18 with each of said pipes, as said space is successively moved 45 into register therewith.

In order to prevent the water under pressure within the chamber 2 from passing out into the respective distributing pipes as the outlet openings 20 are successively moved 50 into register therewith during an upward movement of the plunger and stem, the cup 17 may be carried by a sleeve 25 for limited sliding movements on the stem 15 between the lower cup 18 and a stop-collar 26 on the 55 stem, the sleeve 25 serving as a valve for closing the perforations 20 when the cup 17 is in its lowered position on the stem, as shown in Fig. 2. It is apparent with this construction that upon an upward movement 60 of the stem 15, the frictional coaction of the cup 17 with the casing 1 will tend to hold it stationary within said casing until the stem has moved upward a sufficient distance to place the openings 20 therein into 65 register with the valve sleeve 25 and to bring

the lower cup 18 into contact with the lower end of said sleeve or the cup 17. On a downward movement of the stem 15 the frictional coaction of the cup 17 with the casing 1 causes such cup to remain stationary in its 70 elevated position until the stem has lowered a sufficient extent to move the collar 26 into contact with the upper end of the sleeve 25, thus, effecting an uncovering of the outlet openings 20.

It is evident that I have provided simple and efficient means for obtaining a successive discharge of water under pressure through different conduits from a common supply main, and that the distribution of 80 water from each discharge conduit may be quite accurately regulated as to both time and quantity. It is also evident that in the forms of the invention wherein the lowering movement of the plunger carrying stem is 85 controlled by the same water pressure with which the distributing pipes are supplied, the speed of lowering will depend on the amount of water pressure, so that should the water pressure be low and the discharge of water from the sprinkling system or discharge conduits be consequently slow, the speed of lowering of the stem and plungers will be accordingly reduced. It is thus evident that the speed of lowering 90 movement of the plungers is not constant but varies with the water pressure and also that the quantity of water distributed is 95 substantially constant and does not vary with the pressure.

I wish it understood that my invention is not limited to use in connection with the distribution of water as specifically described herein, and also that it is not limited to the specific arrangement, form or construction 105 of the parts, as it is capable of numerous modifications other than those illustrated without departing from the spirit of the claims.

Having thus described my invention, 110 what I claim as new, and desire to secure by Letters Patent, is—

1. In an apparatus of the class described, means forming a chamber having communicating large and small cylindrical portions, 115 said chamber having communication with a source of fluid supply under pressure and having a plurality of spaced transversely opening outlet passages in its small portion, valve means movable longitudinally in the 120 small portion of said chamber for successively opening communication between said source of supply and different outlet passages, said means causing a closing of each passage at substantially the time of 125 opening of the next passage in order, a plunger attached to said valve means and movable in said large chamber, means for relieving the pressure in the large portion 130 of said chamber at the outer side of said

plunger and means carried by the plunger for regulating the flow of fluid from one side to the other thereof from said source of supply.

- 5 2. In an apparatus of the class described, means forming a chamber having communication with a source of fluid supply under pressure and having a fluid outlet passage opening transversely therefrom, valve
10 means movable in said chamber and adapted during a predetermined portion of its movement in one direction past the outlet passage, to close communication between said source of supply and outlet passage and during
15 the same portion of its movement in the opposite direction to open said communication, and means connected to said valve means and automatically operable to impart predetermined movements thereto.
- 20 3. In an apparatus of the class described, a casing having a fluid inlet passage and a fluid outlet passage opening transversely

therein in spaced relation to said passage longitudinally of said opening, a hollow valve-stem movable in said casing and having longitudinally spaced openings in communication with the interior of said casing, a plurality of plungers mounted on said stem and separating said openings whereby said inlet passage is in communication with said outlet passage through the stem during a predetermined portion only of the stem movement, one of said plungers being movable on the stem and adapted to automatically move over and cover one set of said 35 openings during a movement of the stem in one direction, and fluid pressure controlled means connected to said stem and operable to impart predetermined movements thereto within said casing. 40

In testimony whereof, I have hereunto signed my name to this specification.

JOHN A. BROOKS.
